UNITED STATES PATENT OFFICE

JESSE C. SMITH, OF NEW YORK, N. Y.

REFRIGERATION

Application filed April 7, 1922, Serial No. 550,291. Renewed August 30, 1929.

This invention relates to refrigerating machines or apparatus.

Refrigerating apparatus of the absorption type obtains its cooling effect by the rapid expansion of condensed ammonia gas or anhydrous ammonia. As the expansion takes place heat is absorbed by the gas thereby cooling the surrounding media from which the heat is taken.

10 The usual cycle of operation of devices of this character includes heating a solution of ammonia and water to expel the ammonia gas, cooling the gas under pressure to condense it to a liquid form, rapidly expanding 15 the anhydrous liquid under reduced pressure and absorbing in water or weak liquor the gas formed by the rapid expansion.

Most of the difficulties experienced in refrigerating apparatus of the type described 20 or in refrigeration by the ammonia process have been due to the use of mechanical moving parts such as pumps and to leaking joints and stuffing boxes. Moreover, such refrigerating apparatus has required the use of an 25 electric motor, steam pump or other driving means to operate the moving parts and to maintain the circulation through the system.

One of the objects of this invention is to simplify the process of refrigeration, to utilize 30 a minimum number of parts and to eliminate the use of mechanical moving parts and driving motors.

Another object of the invention is to provide 35 a refrigerating apparatus in which the circulation of the fluid is obtained through the pressure of the gas and is due to the differences in pressure at different parts of the apparatus.

Another object of the invention is to provide 40 a refrigerating device having its parts so constructed and arranged as to insure a continuous and uninterrupted service during the operation of the device.

Another object of the invention is to provide 45 in refrigerating apparatus of the class described, means for insuring an adequate or measured supply of liquid in the various parts of the apparatus where the liquid is utilized.

Another object of the invention is to provide 50 a refrigerating device of the absorption

type so constructed and arranged that the entire cycle of operation is maintained and performed without the use of a motor or similar driving device.

Another object of the invention is to provide 55 refrigerating apparatus so constructed and arranged that it is set in operation by the application of heat and the power used for maintaining the operation and the circulation of the fluid and carrying through of 60 the cycle is derived from the application of heat.

Further objects of the invention will appear 65 from the following specification taken in connection with the drawings which form a part of this application and in which

Fig. 1 is a sectional elevation illustrating 70 refrigerating apparatus constructed in accordance with the invention.

Fig. 2 is a transverse sectional elevation taken substantially on line 2—2 of Fig. 1.

Fig. 3 is a sectional elevation taken substantially on line 3—3 of Fig. 1.

Fig. 4 is a sectional elevation taken substantially on line 4—4 of Fig. 1.

Fig. 5 is a perspective view of a refriger- 75 erator having the refrigerating device mounted thereon.

Fig. 6 is a diagrammatic view illustrating 80 the process of refrigeration and apparatus employed.

Fig. 7 is an elevational view showing a measuring or constant supply device for the pump chambers.

The invention may be briefly described as 85 a process and apparatus for carrying out the various steps of the ammonia absorption refrigeration process in the usual manner but maintaining the circulation of the fluid through the various parts and the continuous 90 operation of the cycle by means of pressure derived from the generation or formation of the ammonia gas.

This is accomplished in the device about 95 to be described by dropping or flowing a strong ammonia solution in water on a hot plate thereby freeing the ammonia. The ammonia gas is conducted to a condenser and is there condensed under pressure to a liquid and the liquid is passed through an expansion 100

valve and from the valve through an expansion coil and is gasified therein by heat absorbed from the surrounding media. From the expansion coil the ammonia gas passes to an absorber and is absorbed by the weak liquor and from the absorber the strong liquor is returned to the boiler or place of application of the heat. The means for maintaining the circulation in the system and for returning the liquor to the boiler includes members which may be termed pumps and these devices are operated entirely by the pressures developed in the process and are not driven by any outside source of power.

Referring to the drawings, attention is particularly directed to Fig. 6 where the connections between the various parts of the apparatus are more clearly shown although the showing in Fig. 6 is somewhat diagrammatic.

The generator or boiler for distilling or separating the ammonia gas from the aqua ammonia is shown at A. This part of the apparatus comprises a casing 10 having an electric hot plate 11 or equivalent heating device, disposed therein and a porous member 12 such as a piece of quartz filter or equivalent material is mounted in the casing 10 above the hot plate and between the incoming liquor and plate.

The quartz filter is composed of fine grains of quartz tightly compressed and then slightly vitrified. The small grains being uneven in shape, do not fit closely and thus interstices or air spaces are formed in the body. The total area of all these small openings is equivalent to several square feet and the cooling surface is confined in a small space and is very compact.

The liquor filters down through the porous member 12 and the supply is so regulated that it drops from the porous member onto the hot plate in a steady stream or one drop at a time, as desired. The vapor immediately rises from the hot plate and passes through the porous member and as it passes upwardly it meets the cool liquor which is passing downwardly through the member 12. This condenses any moisture or water in the vapor which is passing upwardly and separates it from the ammonia gas which passes through the member 12 and into the outlet pipe 13.

The supply of incoming liquor is controlled by a ball float 14 slidably mounted on a stem 15 on the upper end of which is a stop 15^a that operates a ball or valve 16 which is adapted to seat on an inlet port 17.

The pipe 13 conducts the ammonia gas at a pressure of about 125 pounds to a condenser coil B which is immersed in a jacket of water 20. The gas is cooled down by the water and is condensed to liquid ammonia or an anhydrous liquid. The anhydrous liquid passes from the condenser through a pipe 21 and through a thermostatic expansion valve 22

of the usual construction to an expansion coil C. As the gas passes through the condenser coil B and condenses to a liquid the pressure is maintained but in the expansion coil C the pressure is about 30 pounds. In this coil the anhydrous liquid expands rapidly into a gas and in so doing absorbs heat from the surrounding media thereby giving the desired cooling effect. At 30 pounds pressure ammonia evaporates at the temperature of about 30 to 35 degrees Fahrenheit. If a lower temperature is desired a lower pressure must be maintained in the expansion coil. Atmospheric pressure would give minus 12 degrees Fahrenheit.

From the expansion coil C the ammonia gas is conducted through a pipe 23 to an absorber D containing a weak solution of ammonia or a weak liquor under substantially 20 to 30 pounds pressure. The ammonia gas passing from the pipe 23 into the absorber is entirely absorbed by the liquor thereby concentrating the solution and forming a strong liquor. The weak liquor is supplied to the absorber D through a pipe 30 and the supply is controlled by a ball valve 31 which in turn is controlled by a float 32.

The pipe 30 receives the liquor from a cooling coil E and this coil is connected by pipe 33 to the bottom of the generator or boiler A as shown at 34. The passage of the liquor from the cooling coil E to the pipe is controlled by a needle valve 35 or an opening or orifice of a predetermined size. Circulation through the pipe 30 is effected by 90 the difference in pressures between the generator and the absorber.

The means whereby the operation of the cycle just described is maintained and whereby the liquor is returned to the generator or boiler will now be described.

This means comprises one, or preferably, a pair of cylinders F which may be termed pumps and are also submerged in the water jacket 20. The gas is conducted to each of these cylinders through pipes 40 communicating with the pipe 13. The inlet port 41 of each cylinder F is controlled by a ball or equivalent valve 42 which in turn is controlled by a lever 43 actuated by a float 44.

Weak liquor is also conducted to the cylinders F by a pipe 45 which communicates with the pipe 30 and also with inlet pipes 46. The supply of weak liquor passing to the cylinders is controlled in the embodiment of the invention shown in Fig. 6 by needle valves 47.

Strong liquor is conducted to the bottom of each of the pumps F from the bottom of the absorber D. This liquor is conducted through a pipe 50 from the bottom of the absorber to an inlet pipe 51 connected to the bottom of one of the cylinders F, the admission to this pipe being controlled by a check valve 52 shown as a ball valve. The 130

pipe 50 is also connected to an inlet pipe 53 connected to the bottom of the other cylinder and this inlet is controlled by a ball check valve 54.

5 The strong liquor is conducted from the cylinders or pumps F to the inlet port 17 of the generator or boiler A in the following manner. A by-pass 60 communicates with the inlet pipe 51 of the cylinder F and a by-pass 61 communicates in a corresponding manner with the intake 53 of the other cylinder. Each of these by-passes leads to a pipe 62 which in turn communicates with a pipe 63 connected at its other end to the intake port 17 of the boiler or generator A. In the by-passes, however, or between the by-passes of the pipe 62 are ball check valves 64 and 64A which control the passage of the liquor to the pipe 62.

10 20 The rate of flow of the liquor through the pipe 63 and to the heater may be controlled by the valve 35 in pipe 30 since the rate of flow from the generator A through pipes 33 and 30 to the pumps will control the operation of the pumps F and thus the discharge therefrom.

25 30 Before describing the operation of the apparatus I will describe the structure shown in Fig. 7 which has for its object to maintain an adequate supply or a measured quantity 35 of weak liquor in the pump cylinders F. This device consists of a reservoir or constant supply chamber G which is interposed between the pipe 41 and each of the pump cylinders F. A nozzle 70 has one end 71 disposed adjacent the bottom of the chamber G and has its other end 72 extending into and discharging into the cylinder F. A check valve 73 is interposed between the chamber G and the 40 supply pipe 30.

45 50 This apparatus is used to inject a measured quantity of weak liquor into pump F, the measured quantity being just sufficient to completely absorb all of the ammonia gas remaining in the cylinder F after the gas has been cooled.

55 60 The structure shown in Fig. 7 operates as follows. Starting with F filled with an ammonia gas at a pressure of 125 pounds and valve 42 just closed off by ball float 44, the gas in F commences to cool by contact with the water cooled walls of F. This cooling causes shrinkage in volume and naturally a decrease in pressure. In order that the cycle 65 of operation may be hastened the apparatus as shown in Fig. 7 now begins to function. With valve 64A closed by pressure of gas in A, the pipe 72 being the only connection with A, any difference in pressure between A and F will tend to cause a flow of weak liquor from A through 46 past the ball valve 73, into the reservoir G and thence to F. The greater the pressure difference the faster will be the flow. Ball valve 73 is adjusted so that it 70 moves very freely and at a certain velocity

of the liquid, the ball 73 rolls against the seat, where it is held by the difference in pressure between A and F. Now in order to complete the absorption of the remaining gas in F, the expansion of the gas trapped over the 75 weak liquor in G is used to force the weak liquor through the spray nozzle 72, thus completing the absorption of the gas.

75 The operation of the apparatus will now be outlined. When the heat is applied one of the pump cylinders F will be filled with strong liquor and the other one I will assume is empty. As the heat increases the pressure in A also increases due to the vaporizing of the liquor around the heating device 11 and naturally this tends to equalize and become the same in all parts of the system. Thus a flow of liquor is set up in the pipe 33, causing the level of liquor in A to be lowered. In order that this level may be maintained 80 the ball float 14 opens the valve 17, thus permitting liquid to flow from 63 to the top of the filter 12. As the liquor passes down through the porous member 12 and is vaporized it will pass back through the porous member 85 in the form of vapor and will be dehydrated and the ammonia gas will pass through the pipe 13 to the condenser B. In the condenser the gas will be liquefied and the anhydrous liquid will pass through the expansion valve 90 95 100 105 110 115 120 125 130

22, be expanded in the coil C and returned in the form of gas through the pipe 23 to the absorber D. The ball check valve 24 or other suitable valve, is interposed between the absorber D and the pipe 23 to prevent the liquor in the absorber from passing into this pipe, as for instance, when the device is shut down and the gas flow into the absorber is stopped. This absorber contains weak liquor under a pressure of substantially 20 to 30 pounds which will absorb the gas, and the strong liquor will pass from the absorber through the pipe 50. During this operation the gas will also pass from the pipe 13 through one of the pipes 40 to one of the cylinders F. In Fig. 6 gas is shown as passing to the left hand cylinder, since this cylinder is filled with liquor to a sufficient extent to permit ball float 44 to open the ball valve 41. When ball valve 41 is opened the pressure in F is immediately equalized with that in the generator A and pump F being located above the generator A, gravity creates enough pressure upon ball valve 64A to raise it from its seat, and the liquor thus flows through the pipes 62-63 to the intake port 17 of the generator A. When the liquor is being emptied from one of the cylinders F as the left hand cylinder, the liquor is passing into the other cylinder from the absorber D and in Fig. 6 the liquor is passing into the right hand cylinder. This passage of the liquor into the cylinder F from the absorber takes place because of the difference in pressure between the pressure in the absorber D and the pressure in the

cylinder F. The pressure in the absorber D is maintained at about 30 pounds by a regulating valve 22 whereas in the cylinder F gaseous ammonia above the liquor is being decreased in volume and condensed due to the water jacket around the cylinder and also the pressure is lowered because of the further absorption of this ammonia gas by the fine spray of weak liquor admitted through the pipe 46. The admission of the weak liquor is controlled by the difference in pressures between the pressure in the cylinder F and the pressure in the feed pipe 45. This condensation of the ammonia gas will cause the pressure within the cylinder to fall to zero or below and since the pressure in the absorber is substantially 30 pounds the strong liquor will pass from the bottom of the absorber through the pipe 50 and connecting pipe 51 or 53 to the cylinder F. When the liquor has risen in the cylinder sufficiently to open the valve 41 the ammonia gas is again admitted under pressure and the liquor is thereafter emptied out and conducted to the generator A by gravity. It will thus be seen that the pumps or cylinders F operate alternately and maintain a continuous flow of liquid to the generator A.

The embodiment of the apparatus shown in Figs. 1-5 inclusive, is substantially the same as regards the parts as that shown in Fig. 6 and differs therefrom only in that the coils B and E in Figs. 1-5 surround the three cylinders D, F and F. Since the parts correspond in both of these showings corresponding reference characters are used in Figs. 1-5 and in Fig. 6.

In Fig. 5 the device is shown mounted in position on an ice box and the pipes extending through the bottom of the device conduct water to and from the water jacket. The hot plate is also shown as connected to an electric switch plug. The starting and stopping of the operation of the apparatus may be controlled by the manual opening of the electric circuit to the hot plate, or if desired, the operation may be automatically controlled by a thermostat.

From the foregoing specification it will be seen that a simple, practical and effective apparatus has been designed and that the cycle of operation is maintained solely through the difference in pressure of the fluid in the different parts of the apparatus. Thus the strong liquor will be taken into one of the pump cylinders because the pressure within the cylinder is lower than that within the absorber and at the same time the liquid will be fed from the other cylinder by gravity to the generator.

Although one specific embodiment of the invention has been particularly shown and described, it will be understood that the invention is capable of modification and that changes in the construction and in the ar-

rangement of the various cooperating parts may be made without departing from the spirit or scope of the invention as expressed in the following claims.

What I claim is:

1. A refrigerating device comprising a generator, a hot plate, means for feeding liquor to said hot plate, a condenser, means for conducting gas from the generator to the condenser, an expansion coil receiving the condensed liquid from the condenser, an absorber receiving the gas from the expansion coil, a pump chamber connected to the absorber, means for feeding generator gas to said chamber, condensing the gas to lower the chamber pressure below the absorber pressure thereby causing the liquor to pass from the absorber to the chamber, valve mechanism in the pump chamber for controlling the gas admission thereto, said mechanism being controlled by the liquid level in the chamber, and a conduit connecting the pump chamber to the generator.

2. Apparatus of the class described comprising a generator for freeing ammonia gas from aqua ammonia, a condenser for liquefying the gas, expansion means for gasifying the liquid ammonia, an absorber for taking up the gaseous ammonia, and cooling means for receiving and condensing ammonia gas from the generator thereby creating a reduced pressure, said last named means being operable by the reduced pressure to withdraw the liquor from the absorber and return the liquor to the generator.

3. Apparatus of the class described comprising a generator for freeing ammonia gas from aqua ammonia, a condenser connected to the generator for liquefying the gas, expansion means connected to the condenser for gasifying the liquid ammonia, an absorber connected to the expansion means for taking up the gaseous ammonia, a condenser chamber connected to and receiving and condensing free ammonia gas from the generator, a connection from the generator to the chamber for conducting liquor thereto, a conduit connecting said absorber to the chamber and a liquor return conduit for conducting the liquor from the chamber to the generator.

4. Apparatus of the class described comprising a generator for freeing ammonia gas from aqua ammonia, a condenser for liquefying the gas, expansion means for gasifying the liquid ammonia, an absorber for taking up the gaseous ammonia, and means for receiving and condensing ammonia gas from the generator thereby creating a reduced pressure lower than the pressure in the absorber, a connection between said means and said absorber, said last named means being located above and connected to the generator, whereby the liquor withdrawn from the absorber into said means, will flow by gravity to the generator, withdrawing the liquor

from the absorber and returning the liquor by gravity to the generator.

5. Apparatus of the class described comprising a generator for freeing ammonia gas from aqua ammonia, a condenser for liquefying the gas, expansion means for gasifying the liquid ammonia, an absorber for taking up the gaseous ammonia, means for receiving and condensing ammonia gas from the generator thereby creating a reduced pressure, said last named means withdrawing the liquor by reason of the reduced pressure from the absorber and being located above and connected to the generator whereby liquor can flow by gravity to the generator and means for controlling the supply of gas received by the last named condensing means.

6. Apparatus of the class described comprising a generator for freeing ammonia gas from aqua ammonia, a condenser for liquefying the gas, expansion means for gasifying the liquid ammonia, an absorber for taking up the gaseous ammonia, means for receiving and condensing ammonia gas from the generator thereby creating pressure lower than the pressure in the absorber, said last named means due to its reduced pressure operating to withdraw the liquor from the absorber and being located above and connected to the generator whereby liquor can flow by gravity to the generator, and float controlled valve mechanism for controlling the supply of gas received by the last named condensing means.

7. Refrigerating apparatus comprising a generator for generating ammonia gas, condensing, expansion and absorbing mechanism, connections between said generator and condenser, condenser and expansion mechanism, expansion mechanism and absorbing mechanism, and pumping mechanism connected to the absorber and to the generator for withdrawing the liquor from the absorbing mechanism and returning the liquor by gravity to the generator comprising a cylinder, means for conducting gas thereto, means for condensing gas in said cylinder and means for feeding a measured supply of liquor from the generator to the cylinder.

8. Refrigerating apparatus comprising a generator for generating ammonia gas, condensing, expansion and absorbing mechanism, connections between said generator and condenser, condenser and expansion mechanism, expansion mechanism and absorbing mechanism and pumping mechanism connected to the absorber and to the generator for withdrawing the liquor from the absorbing mechanism and returning the liquor by gravity to the generator comprising a cylinder, means for conducting gas thereto, means for condensing gas in said cylinder and pressure controlled means including a reservoir for feeding a measured supply of liquor from the generator to the cylinder.

9. Apparatus of the class described comprising a heat actuated generator for freeing ammonia gas from aqua ammonia, a condenser connected to the generator for liquefying the gas, expansion means connected to the condenser for gasifying the liquid ammonia, an absorber connected to the expansion means for taking up the gaseous ammonia, and means disposed above the level of and connected to the generator for receiving and condensing ammonia gas from the generator thereby creating a pressure below the pressure in the absorber, said last named means due to the reduced pressure withdrawing the liquor from the absorber and returning the liquor by gravity to the generator.

10. Refrigerating apparatus comprising means for generating ammonia gas, means for liquefying the gas, an expansion coil for gasifying the liquid, an absorber for absorbing the gas, means utilizing gas formed by the generating means to produce a difference in pressure in different parts of the system, said last named means being connected to the absorber and the generator for receiving and condensing free gas from the generator and being controlled by the variations in pressure and the amount of liquid therein for withdrawing the liquor from the absorber and returning the liquor from the absorber to the generator and thereby completing the cycle of operation, said pressure controlled means being constructed and arranged to operate alternately to withdraw liquor from the absorber and return the liquor to the generator.

11. Apparatus of the class described, comprising a generator, a condenser, an expander, and an absorber, and means for maintaining the circulation of fluid and the cycle of operation through said apparatus, comprising pumping and condensing mechanism connected to said generator and absorber, said pumping mechanism operated entirely by the fluid in the system and depending for its operation on variations in pressure in different parts of the apparatus, and means for feeding a measured quantity of liquor from said generator to said pumping mechanism.

12. In a refrigerating apparatus of ammonia absorption type having a generator, a condenser, an expander, and an absorber, means for maintaining the circulation of fluid and the cycle of operation, comprising pumping and condensing mechanism connected to said generator and absorber, said mechanism being operated entirely by the fluid in the system, and depending for its operation on the variations in pressure in different parts of the apparatus, and by the amount of liquid in the pumping mechanism, and pressure control means for feeding a measured quantity of liquid from said generator to said pumping mechanism.

13. A refrigerating device comprising a generator having means for applying heat to

ammonia liquor to free the ammonia, a condenser connected to the generator, an expansion coil connected to the condenser, an absorber receiving the gas from the expansion coil, a pump, connections between said pump and said absorber and between the pump and the generator, said pump receiving and condensing free gas from the generator and operating to return liquor from the absorber to said generator, said pump being controlled by the generated gas and operated by the differences in pressure in the pump and absorber and the amount of liquid in the pump for returning the liquor from the absorber to the generator.

14. A refrigerating device comprising a generator having means for applying heat to ammonia liquor to free the ammonia, a condenser connected to the generator, an expansion coil connected to the condenser, an absorber receiving the gas from the expansion coil, and a pair of alternately operable pumps connected to the absorber and to the generator, said pumps receiving and condensing free gas from the generator and operating alternately to return liquor from the absorber to the generator, said pumps being controlled by the generated gas and operated by the differences in pressure in the absorber and pumps and by the amount of liquid in the pumps for feeding a constant and uninterrupted supply of liquor from the absorber to the generator, said pumps being connected to the absorber and to the generator.

In witness whereof, I have hereunto set my hand this 4th day of April, 1922.

JESSE C. SMITH.
